Primary Examiner — Elizabeth A. Albert*(74) Attorney, Agent, or Firm* — Patterson Thuente
Pedersen, P.A.(57) **CLAIM**

The ornamental design for a vertical farm station, as shown and described.

DESCRIPTION

FIG. 1 is an isometric view of a vertical farm station showing my new design.

FIG. 2 is a front view of the vertical farm station of FIG. 1.

FIG. 3 is a side view depicting the vertical farm station of FIG. 1.

FIG. 4 is a top view depicting the vertical farm station of FIG. 1.

FIG. 5 is a bottom view depicting the vertical farm station of FIG. 1.

FIG. 6 is a rear view of the vertical farm station of FIG. 1.

FIG. 7 is a perspective view of the vertical farm station of FIG. 1; and,

FIG. 8 is an alternative perspective view of the vertical farm station of FIG. 1.

The broken lines in FIGS. 7 and 8 show portions of the vertical farm station that form no part of the claimed design.
